UNITED STATES PATENT OFFICE.

ANDREW M. COYLE, OF NEW YORK, N. Y., ASSIGNEE TO OTIS ELEVATOR COMPANY, OF JERSEY CITY, NEW JERSEY, A CORPORATION OF NEW JERSEY.

MULTIPLE HOISTING APPARATUS.

954,022.

Specification of Letters Patent.

Patented Apr. 5, 1910.

Application filed October 11, 1905. Serial No. 282,234.

To all whom it may concern:

Be it known that I, ANDREW M. COYLE, a citizen of the United States, residing at New York city, in the county of New York and State of New York, have invented a new and useful Improvement in Multiple Hoisting Apparatuses, of which the following is a specification.

My invention relates to hoisting apparatus and particularly theater curtain hoisting apparatus.

The object of my invention is the provision of simple, compact and efficient means for raising and lowering theater curtains singly or in groups in any desired manner.

A further object of my invention is to provide one or more of the units of multiple hoisting apparatus with a releasing device which shall allow the curtain to drop quickly and independently of the driving mechanism; and also to provide such curtain with a retarding device by which the rate of speed of descent of said curtain may be varied and regulated.

Other objects of my invention will appear hereinafter, the novel combination of elements being set forth in the claims hereto appended.

In the accompanying drawings, Figure 1 represents in front elevation my multiple hoisting apparatus with an electric motor connected thereto for driving the same; Fig. 2 is a side and sectional elevational view taken on the line A—A, Fig. 1, looking in the direction of the arrows a—a; Fig. 3 is a similar view taken on the line B—B, Fig. 1, looking in the direction of the arrows b—b; Fig. 4 is a detail view; and Fig. 5 is a wiring diagram illustrating the operation of the various apparatus singly or in groups.

In Fig. 1 is shown a frame-work 1 mounted on a bed-plate 2 at the right-hand end of which is also an electric motor 3. Within the frame-work 1 are mounted the frames 4, 5, 6 for electromagnetic coils or solenoids 7, 8 and 9. Between the motor and frame-work is shown a dash-pot illustrated and claimed in the patent to A. M. Coyle, #838,169, granted December 11, 1906, improvement in dash pots.

The motor shaft 10 is extended to the left as viewed in Fig. 1 through the frame-work and is supported in bearings in said frame-work at 11 and 12. Distributed along the shaft 10 and keyed thereto are a series of

friction driving disks 13, 14, 15, with leather, rubber or the like, 16, 17, 18, respectively, on their peripheries. These disks are adapted to drive friction wheels 19, 20 and 21, respectively, but the latter are normally held out of engagement therewith as shown in Fig. 2. The friction wheels preferably have smooth peripheries, but may be provided with leather, rubber or the like on their peripheries, if desired. Each friction wheel is part of an independent hoisting mechanism and the connections for each being substantially the same, a description of that for one will suffice for all. Referring, therefore, to Fig. 3, it will be seen that the friction wheel 20 is fixed to the shaft 22 which is mounted in a bearing at the end of the arm 32 which is pivoted on the rod 24. This rod extends across the front of the frame-work 1, being fixed thereto at 27 and 28.

From Fig. 4 it will be seen that the sleeve 30 which is loosely mounted on the bar or rod 24 is provided with two inwardly-extending arms, 32, 32', but only one arm may be here used if desired. The inner ends of these arms serve as bearings and supports for the shaft 22, to the ends of which are secured the friction wheel 20 and the pinion 47, the said friction wheel and pinion being mounted on the ends of the shaft 22 just outside of the arms 32, 32'. The length of the shaft is substantially equal to the length of the cylinder or sleeve 30 and the hub 33, or approximately equal in length to the combined width of the hoisting drum 52, its gear 49, and the friction wheel 20. Fulcrumed on the rod 24 but independently of the arms 32, 32', are vertical arms 25, 35, 36, each provided with a brake-shoe 26 which is adapted to contact with the periphery of the friction wheels. Normally, strong springs 37 effect a lifting of the friction wheels from engagement with the friction disks (Fig. 2).

In Fig. 2 is shown a sectional view of one of the electromagnets and a spring 37 connected thereto. A stud bolt 39 passes through the axis of the helical spring 37 and also through holes in the holding cups 40 and 46, the latter cup being secured to the left-hand end of the magnet frame 4. After passing through the cup 46 the stud bolt 39 is screwed into the magnet core 38 so as to be rigid therewith while its other end is provided with nuts 41 outside the cup 40 for adjusting the tension of the spring 37. Nor-

5 mally, this spring tends to move the core 38 to the left and with it the stud-bolt 42 which is screwed into the right-hand end of the core. The other end of the bolt 42 passes through a hole 45 in the lower end of the lever 25 and is provided with a retaining nut 44 by which the position of the shoe may be regulated with respect to the friction wheel 19.

10 In Fig. 2 it is seen that the core is shown in such position that when the solenoid 7 is excited with electric current the magnet will operate to draw its core to the right against the action of the spring 37 and in doing so move the lever 25 together with its brake shoe 26 to the right. Inasmuch as the friction wheel 19 is normally supported by the brake shoe out of contact with the friction disk the latter will rotate without producing 15 any effect. When, however, the brake shoe is moved to the right, as explained, the friction wheel is let down on the friction disk and will be driven thereby. Upon further movement of the shoe it will be drawn entirely out of contact with said friction wheel.

20 The small pinions 47 on the shafts 22 mesh with the large gear wheels 48, 49 and 50. These gear wheels are rigidly fastened to the hoisting drums 51, 52 and 53, respectively, which are loosely mounted on the rod 54 fixed to the frame-work 1 or said gear wheels and drums are respectively connected to each other so as to rotate together. Each gear wheel, as 49, Fig. 3, meshes with 25 a small gear 55 which is adapted to operate stop motion apparatus 56 mounted in the housing 57 on top of the machine. This stop motion apparatus serves the purpose of opening the circuit closer 58 to deener- 30 gize the electromagnet corresponding thereto, when the curtain reaches either limit of its travel. It is to be understood that each hoisting drum is provided with such a stop-motion apparatus and that when it operates 35 to open its circuit closer it has no effect on the other hoisting mechanisms adjacent to it. This operation is automatic and is more fully explained hereinafter in connection with the wiring diagram shown in Fig. 5. 40 The specific form of the preferred stop-motion apparatus is not fully shown herein but the same will form the subject-matter of a separate application, and moreover *per se* forms no part of the present invention, as 45 any well-known stop-motion apparatus such as those used in connection with electric elevators may be used if desired.

50 In case of emergency, as when a fire occurs in a theater, it may be deemed necessary to drop the asbestos curtain much more quickly than ordinarily. I have therefore provided a pneumatic releasing device which normally may be filled with compressed air. This air may be released by 55 the blowing of a fuse due to the fire, if de-

sired, so that the dropping of the asbestos curtain shall be entirely automatic.

In Fig. 2 is shown the hoisting apparatus modified for this purpose. A lug 65 is secured near the inner end of the arm 32 through a hole in which passes loosely a vertical rod 61 which may be secured to a flexible diaphragm in the pneumatic device 59. This pneumatic device is secured in proper position by means of the brackets 60 to the frame-work 1. On the rod 61 intermediate the diaphragm and the lug 65 is a compression spring 64 held in place by the cup 63 and nut 62. The extreme lower end of the rod 61 is provided with a nut 66 which is adapted to engage the lug 65 but is normally out of engagement therewith as shown in Fig. 2.

The operation of this construction, Fig. 2 is as follows: Normally the spring 37 acts 85 to lift the friction wheel 19 out of engagement with the friction disk 13 but the pinion 67 remains in mesh with the train of gears connected to the hoisting drum. The spring 37 is made of sufficient strength 90 to lift the friction wheel 19 and its pinion 67 and also act against the spring 64 of the pneumatic device. When the air pressure on the upper side of the diaphragm in the casing 59 is relieved the rod 61 moves 95 upwardly under the action of the flexible diaphragm in the casing 59 and with it the nut 66 which engages the lug 65 and carries the shaft 22 upwardly so far that the pinion 67 is taken out of engagement with 100 the train of gears between the same and the drum gear 48. The weight of the curtain will now act to lower the same independently of the friction-wheel. The lowering of the curtain thus by gravity may be too 105 quickly done, so that if desired a dash-pot mechanism 69 (Fig. 1) may be connected with the drum gear 48 by means of a pinion 75 which meshes with the same and is mounted on the shaft 73. This shaft is 110 mounted in fixed bearings in the upper portion of the frame-work 1 and has secured to it at its right-hand end, as viewed in Fig. 1, a bevel gear 72 which meshes with a similar bevel gear 71. The latter is fixed to the upper end of the dash-pot piston rod 10 which is screw-threaded at its lower end and is adapted to pass through a threaded opening in the center of the dash-pot piston. This particular form of dash-pot *per se* 115 forms no part of the present invention but is disclosed and claimed in the patent hereinbefore referred to. An ordinary form of dash-pot may be used if desired but the one described in said patent is deemed preferable.

120 It is seen that the shaft 73 is extended toward the right and is provided at its outer end with a squared portion 74 on which a crank may be fitted to manually raise the 130

curtain, if desired, when the pneumatic device may again be set so as to release the arm 32. When this occurs the spring 64 may act to force the pinion 67 into mesh 5 with the gear 75 and also force the friction wheel 19 into intimate contact with the brake shoe 26. This holding power or braking effect is necessary inasmuch as asbestos curtains are usually the heaviest. The tension of the spring 64 and consequently the frictional engagement between the wheel 19 and its driving disk 16 may be varied or regulated by means of the nut 62. With the curtain hoist illustrated in Fig. 3, it should 10 be noted, no spring, as 64, is necessary to hold the friction wheel and disk in contact, this being effected by the weight of the curtain acting through the gear 49 and pinion 47 to move the shaft 22 and consequently 15 the friction wheel 20 in a downward direction. This is evident when the hoisting rope is considered passing upwardly from the drum 52 in Fig. 3. The load connected to the hoisting rope tends to rotate the said 20 drum in a clockwise direction. The gear 49 acts on the pinion 47 tending to rotate it in a anti-clockwise direction, and at the same time swing the arm 32 on the shaft 24 as a fulcrum. This necessarily results in a downward 25 thrust on the wheel 20, causing the latter to be brought into frictional engagement with the driving member 13 in proportion to the load. Or, if the driving member 13 be considered rotating in an anti- 30 clockwise direction so as to wind the hoisting rope on the drum, the friction wheel 20 will rotate in a clockwise direction and the pinion 47 will tend to travel downwardly on the gear 49. The greater the 35 load to be lifted the greater this tendency, and, therefore, the greater the frictional engagement between the friction wheel 20 and the driving member 13. Although I have 40 shown this feature of my invention in hoisting apparatus, it is to be understood that it may be applied elsewhere, as the gear 49 may be connected to various devices to be operated, and whenever the load varies the frictional connection of the driving apparatus 45 varies. Furthermore, I do not wish to be limited to the form of intermediate mechanism between the driving member 13 and the driven member 52, nor to the means illustrated which acts with such intermediate mechanism to automatically regulate 50 the driving friction so that the latter will be in proportion to the load. For instance, the lever 32 may be fulcrumed on the drum shaft 54, or an arc-shaped slot 55 may hold the wheel 20 from lateral displacement and limit its upward movement, but permit the application of the brake wheel 60 keeping the pinion 47 in mesh to the gear 49. Inasmuch as the driving shaft 10 and 65 the wheels, disks, or rollers 13 mounted

thereon move together as a single device, it is obvious that the shaft 10 and members 13 may be replaced by a shaft of enlarged diameter or by a shaft and a single drum mounted thereon. It may be said, further, 70 that if the periphery of such a drum and the peripheries of the wheels 20 are covered with leather, rubber, cotton or the like, the gearing ratio may be smaller than when metal peripheries are brought into frictional 75 engagement. Furthermore, in order that the same motor may be used to raise the heavier asbestos curtain, reducing gears 75 and 76 are fixed to the shaft 77 so as to mesh respectively with the pinion 67 and 80 drum gear 48. It is seen that the gear 75 is much larger than the small gear 76. The ratio of these two gears, as well as that of any other set or of all the gears, may be varied as desired in a well-known manner. 85 If the reducing gear is omitted the spring 64 may also be omitted, the action then being the same as explained in the last paragraph in reference to the structure shown 90 in Fig. 3.

Referring now to Fig. 5, it will be explained how the hoisting mechanisms may be brought into operation one after another or in groups, as desired, from a single station, where, by the manipulation of a bank of push-buttons and a switch, the electromagnetic releasing devices may be controlled. Fig. 5 represents diagrammatically the apparatus and system of circuits for carrying out these results. + and — designate 95 the main lines from the source of supply of constant potential, and 78 is the main line switch. 79 designates the armature of a motor having a shunt field 85. 80 and 81 are reversing switches and 83 the starting resistance. 82 is a manual switch for controlling the accelerating magnets 91. 84 designates the bank of push-buttons by means of which one or more of the brake magnets 86 may be selected.

The electric motor is shunt wound and has preferably a very strong field which may be governed if desired between the limits of approximately 600 to 1200 revolutions per minute by inserting resistance in circuit with the field winding. In the main circuit there are shown four starting resistances 87, 88, 89 and 90 which are controlled by the accelerating magnets 92, 93, 94 and 95. These accelerating magnets are in turn controlled 115 by the manual switch 82. The main circuit contains also slow speed resistances, as for instance the resistances 96 and 97 which are controlled by the slow speed magnets 98 and 99 which are also connected to the manual 120 switch 82.

The reversing switches 80 and 81 each comprise an electromagnet 100 and 101 having the cores 102 and 103, respectively, which are fixed to the bars or plates of insulation 130

104 and 105. These plates each carry three contacts 106, 107, 108 and 109, 110, 111 which are adapted to engage the fixed contacts 112, 113, 114 and 115, 116, 117, respectively, 5 upon the energization of the magnet 100 or 101. The movable contacts 106, 107 and 108 are connected respectively to the binding posts 118, 119 and 120 by means of flexible conductors; the movable contacts 109, 110 and 111 are likewise connected to the binding posts 121, 122 and 123. The binding posts 119 and 122 are connected respectively to the binding posts 124 and 125 of the stop-motion and brake circuits hereinafter described. The binding post 118 is connected by the conductor 126 to the brush 127 of the motor-armature 79, the other brush 128 being connected by the conductor 129 to the resistances 90 and 96. The binding posts 20 120 and 123 are connected together and by wire 133 to the resistance 87 and also to the fixed contacts 134', 135', 136' and 137'. It should also be noted that a wire 130 leads from the wire 126 to the fixed contacts 131 and 132.

Referring now to the manual controlling switch 82 it will be seen that the same comprises a plurality of arc-shaped fixed contact strips concentrically arranged. These strips 30 may be secured to a base of slate or other insulating material. The controlling switch is here shown made of insulating material with contact strips or bridging pieces 134 and 135 secured to it. This lever may be 35 of other material, however, and the bridging pieces separated electrically from it by means of insulation.

In order to start the motor the lever 141 is moved to the right or left depending 40 upon the direction in which the motor is to be run. Normally, that is, when the lever 141 is in central position, as shown, the pieces 134 and 135 bridge respectively the strips 136, 137 and the strips 139 and 140. 45 The strip 139 is electrically isolated. When the lever 141 is moved to the right to the position indicated by the dotted lines 142, the piece 135 will engage the strip 143. This will result in closing the following circuit: 50 from the positive main through the wire 144, to and through the coil 101, wire 145, strip 143, bridging contact 135, circular contact strip 140, wires 146, 147 and 148 to the negative main.

55 The closing of the circuit just traced effects the closing of the reversing switch 81 which establishes a circuit through the motor-armature as indicated by heavy lines and which may be traced as follows:--from the positive main by wire 144, to and through the contacts 115, 109, wires 126, 149, brush 127, motor-armature 79, brush 128, wire 129, resistances 90, 89, 88 and 87, wire 133, contacts 111, 117, and wire 148 to 60 the negative main. There is also established

a circuit in shunt to the armature from wire 130 by wire 150, to contact strip 137, and through bridging contact 134, strip 136, wire 151, magnet 98, wire 152 to the point 153 where the wire 129 from the brush 128 joins the resistances 96 and 90. The energization of the slow-speed magnet 98 will cause the movable contact 154 to engage the fixed contact 131 and insert the resistance 96 in parallel with the armature through wire 130 to the point 153. The circuit of the shunt field 85 is also closed from binding post 122 through wires 155, 156, 157, 147, and 148 to the negative main. The motor will now start with the resistances 87, 88, 89 and 90 in series with the armature and the resistance 96 in parallel with the armature, this being the condition of slowest speed.

Let the switch lever 141 be moved a little farther toward the right so that the bridge contact 134 shall engage the strip 138 as indicated by the dotted line 189. The space between the strips 136 and 138 is a little less than the width of the bridge contact 134 so that the latter will engage the strip 138 before it leaves the strip 136. As soon as the contact 134 engages the strip 138, current may flow through wire 150, strip 137, contact 134, strip 138, wire 158 to the other slow speed magnet 99 and by way of wire 152 to the point 153. When the contact 134 leaves the strip 136 the magnet 98 is deenergized and the contacts 154 and 131 separated. Before this occurs, however, the contacts 159 and 132 are connected by the magnet 99 so that when contact 134 engages the strip 138 alone, both the resistances 96 and 97 will be placed parallel to the motor-armature. The resistance parallel to the armature is therefore increased and the speed of the motor slightly accelerated. A further movement of the lever 141 to the right onto contact strip 159 will cause current to flow by way of wire 163 through resistance 164 and accelerating magnet 92, wires 165, 152 to point 153. The movable contact 166 will be drawn up against the fixed contact 134' and thus short-circuit the resistance 87. The next step occurs when the contact 134 leaves the strip 138 when the magnet 99 will be deenergized and the resistances 96, 97 removed from the circuit. The resistances 88, 89 and 90 are now in series with the armature, the motor running at an increased speed.

When the contact 134 is moved onto contact 160 current flows through wire 167, resistance 168, coil 93, coil 92, wires 165, 152 to point 153. It will be noticed that although the resistance 164 is cut out by this last operation the coil 92 remains in circuit. The resistance 168 is lessened to an amount approximately equal to the resistance of the coil 92 so that the amount of current shall be about the same as before. When the coil 130

93 is energized the contacts 135, 171 will be closed and both the resistances 87 and 88 short-circuited. This will result in an increase of speed of the motor. In a similar manner also the resistances 89 and 90 are short-circuited by a further movement of the lever 141 to bring the motor up to full speed.

It should be noted that the coils 92, 93, 94 and 95 are so connected with the resistances 164, 168 and 170 that the amount of current through the energized coils remains the same whether one or more are energized. That is, when only the coil 92 is energized the resistance 164 is sufficient to cut down the current to what it will be when all the coils are connected in series and all of them energized. The difference between the resistances 164 and 168 is equal to the resistance 20 of the coil 92 and the difference between the resistances 164 and 170 is equal to the combined resistances of the coils 92 and 93. It is also to be noted that with this arrangement of accelerating magnets to control the 25 starting resistance, I am enabled to bring the speed of the motor up to any speed desired dependent upon the position of the manual controlling switch. Furthermore, by returning the switch lever 141 I am enabled to 30 reduce the speed of the motor to any point dependent upon the position of said lever. In other words, the speed of the motor is always dependent upon the position of the switch lever 141 and may be increased or 35 decreased in speed at will. It is desirable to proportion the starting resistances so as to give the widest possible range of speed for the motor.

Referring to the push-buttons 84 which 40 are adapted to control the brake magnets 86, it will be noticed that said push-buttons are each provided with two electro-magnets each tending to operate the push-buttons in the same direction. The upper line of 45 solenoids 177 are connected in series with each other and are normally energized by current passing from the positive main, to and through the contact 116, wire 174, contacts 175, wire 176, solenoids 177, and wires 50 157 and 147 to the negative main. Current is always passing through this circuit when the main line switch 78 is closed but the intensity of magnetism induced in the solenoids of the upper line of electromagnets is 55 insufficient to close the series of contacts 178 of the push-button circuits. When, however, a push-button is pressed in to close one of the sets of contacts 178 the electromagnet 177 of that push-button will have sufficient 60 strength to hold it closed. So long as the manual controlling switch 82 remains in central position and neither reversing switch is closed the contacts 175 will remain closed and the operation of one or 65 more of the push-buttons 84 will have no

operative effect except to set them in readiness to energize the brake magnets and thus automatically connect a hoisting apparatus to a revolving friction disk. That is, the circuit through the upper line of solenoids 70 being a holding or retaining circuit, will serve to hold a button pressed in after once having been operated so that any particular group of curtains may be selected to be hoisted before-hand. Upon the operation 75 of the automatic limit switches the buttons will be released to return to their normal positions.

Each of the brake magnets 86 is provided with a down limit switch 180 and an up limit switch 181, the coils of the magnets 86 being connected to them at intermediate points. All of the down limit switches are connected to the binding posts 124 and the up limit switches to the binding posts 125. 80 It will be apparent that when one reversing switch is closed the other is in open position and that therefore the circuit from the positive main to one set of limit switches is always broken. For instance, the down limit 85 switches cannot convey current when the movement of the apparatus is upward; the same condition holds with regard to the up limit switches whose circuits are broken when the "down" reversing switch is operated.

As soon as the current begins to flow in the shunt field circuit the magnet 182 inserted therein separates the contacts 175, which has the effect of deenergizing the upper line of electromagnets 177 of the push-button apparatus 84. The push-buttons which had been operated would then fly out to their normal positions by reason of the springs 183, unless held in by the action of 105 one of the brake magnet circuits.

Assuming that all the push-buttons have been operated and are held in circuit closing position by the upper line of electromagnets 177, let the switch lever 141 be moved to 110 the right to operate the "up" reversing switch. The shunt field circuit being closed the magnet 182 will be energized to separate the contacts 175 to break the circuit of the magnets 177. But substantially 115 at the same time that this occurs current flows from the positive main to the contacts 116, 110, binding posts 122, 125, and in parallel through the circuits 185, the "up" limit switches 181, brake magnets 86, circuits 186, electromagnets 184, contacts 178, to the wire 157, wire 147 and thence to the negative main. The electromagnets 184 will therefore be energized to hold the push-buttons in pressed-in position and consequently maintain the selected brake magnets energized. If a number of push-buttons less than all be energized, those which have not been operated will remain inoperative by reason of the contacts controlled thereby re- 130

maining in open position. The brake magnets in series, respectively, with the electro-magnets 184 of such push-buttons will consequently not be energized.

5. The motor having been put in motion, its speed may be varied as desired and the brake magnets corresponding to the operated push-buttons will release their brake apparatus to effect the actuation of the corresponding 10 hoisting drums. The drums will continue to revolve until the brake circuit is broken by the stop-motion apparatus. The push-button is then automatically released but the motion of the motor may continue, leaving 15 the drum and consequently the curtain in the position determined by the setting of the stop-motion. When the controlling switch 82 is brought back to central position, the motor will, of course, stop, a brake being applied automatically which is released by means of a brake magnet 187 whenever the 20 motor is operated. In this position of the controlling switch no current flows through the shunt field so that the contacts 175 automatically close and the circuit through the 25 holding coils of the electromagnets 177 is again established.

Any suitable form of stop-motion apparatus may be used in connection with the 10 curtain hoisting apparatus herein disclosed but I prefer to use a particular construction, the housing of which is shown at 57 in Figs. 1, 2 and 3, incloses a plurality of cams 56 one for each of the limit switches. The 15 cams are rotated by means of the gear mechanism 75', 55, etc., which mesh with the drum gears 48, 49, etc., respectively. At the desired limit of movement of the hoisting drum the cams 56 operate a lever 188 to 20 which is secured the circuit closer 58 of one of the limit switches. It is to be understood that there are two circuit-closing levers 188 connected to each drum, one lever to operate the "up" limit switch and the other 25 the "down" limit switch.

When the controlling switch lever 141 is moved to the right the curtain will travel upwardly until the upper limit switch is operated and when the lever 141 is moved to 10 the left the curtain will be lowered until the lower limit switch is operated.

Although I have herein shown only one form of my invention, I desire it to be understood that modifications of the details of construction and arrangements of parts may be made by those skilled in the art without departing from the spirit and scope of the invention herein disclosed and claimed.

What I claim and desire to have protected by Letters Patent of the United States is:—

1. The combination with multiple hoisting mechanism, of rolling frictional driving mechanism therefor, and means for operating said driving mechanism at will.

2. The combination with multiple hoist-

ing mechanism, of rolling frictional driving mechanism therefor, and electro-mechanical means for operating said frictional driving mechanism.

3. The combination with multiple hoisting mechanism, of frictional driving mechanism therefor, brakes for said driving mechanism, and means for operating said brakes.

4. The combination with multiple hoisting mechanism, of frictional driving mechanism therefor, brakes for said driving mechanism to effect a stopping of the hoisting mechanism, and electro-mechanical apparatus for operating said brakes.

5. The combination with multiple hoisting mechanism, of driving mechanism therefor, brake apparatus for said driving mechanism, and means for operating any portion of said brake apparatus to disconnect parts of the driving mechanism and positively retard the corresponding portion of the hoisting mechanism.

6. The combination with multiple hoisting mechanism, of frictional driving mechanism therefor, brake apparatus for said driving mechanism to effect a stopping of individual portions of the hoisting mechanism, and electro-mechanical means for operating said brake apparatus to release a selected portion thereof and permit corresponding parts of said driving apparatus to be connected to effect the operation of the selected portion of the hoisting mechanism.

7. The combination with a hoisting drum, of a friction wheel, spur gearing between the drum and wheel, means for driving said friction wheel to effect a movement of the hoisting drum, a brake associated with said driven friction wheel, and means for operating said brake to retard the friction wheel and disengage the same from the driving means.

8. The combination with hoisting mechanism, of frictional driving mechanism therefor, spur gearing between the hoisting and driving mechanisms, means for disconnecting parts of said driving mechanism and effecting a stopping of said hoisting mechanism, and means for actuating said disconnecting means to effect the operation of said mechanism.

9. The combination with a hoisting drum, of a friction wheel connected thereto, spur gearing between the drum and wheel; a friction member for driving said friction wheel to effect the operation of said hoisting drum, means for disconnecting said friction wheel from said friction member and retarding the motion of said wheel, and means for operating said disconnecting means.

10. The combination with a hoisting drum, of a friction wheel, spur gearing between the drum and wheel, a friction member for driving said wheel, means comprising a

brake for separating the drum and wheel and braking the latter, and means for operating said brake.

11. The combination with a hoisting drum, of a friction wheel geared thereto, means for driving said friction wheel, electrically controlled means for lifting said friction wheel to disconnect the same from said driving-means, and means for operating said lifting means.

12. The combination with a hoisting drum, of a wheel, spur gearing between the said drum and wheel, a swinging arm carrying said wheel, a driving member, a brake for said wheel, and means for operating said brake to disconnect said wheel and said driving member and effect a stopping of the hoisting drum.

13. The combination with a hoisting drum, of a friction wheel connected thereto, a driving member, a swinging arm carrying said friction wheel, a swinging brake, a rod on which said arm and brake are pivoted, and means for operating said brake to disconnect said friction wheel and driving member, and effect a stopping of the drum.

14. The combination with a hoisting drum, of a friction wheel connected thereto, a driving member, a swinging arm carrying said friction wheel, a brake shoe, a swinging brake arm, a single supporting means for said arms, and means for actuating said brake arm to apply said brake shoe to said friction wheel and lift the same out of engagement with the driving member, and means for actuating said brake arm to release the brake shoe and permit said friction wheel to fall into engagement with said driving member.

15. The combination with a hoisting drum, of a wheel, a pinion connected with said wheel to rotate therewith and connected also to said drum, an arm carrying said wheel and said pinion, means for driving said wheel, and brake mechanism for connecting or disconnecting said wheel and stopping the hoisting drum.

16. The combination with a hoisting drum, of a combined brake wheel and friction wheel, a friction driving member, a swinging arm carrying said brake wheel, a brake, means for normally holding said brake applied and the brake wheel out of engagement with the driving member, and electro-magnetic means for actuating said brake to release the same and to effect a connection of said brake wheel and driving means.

17. The combination with a driven member, of a frictional driving member, and intermediate connecting means between said members to effect a variation of the driving friction in proportion to the variation of load connected to said driven member.

18. The combination with a movable member, of a friction wheel gear connections be-

tween said parts, a frictional driving member, and means retaining said friction wheel in position but permitting movement thereof as a whole to effect a variation of frictional contact with the driving member as the load on said movable member varies.

19. The combination with a winding drum, of a frictional driving member, a friction wheel geared to said drum, and means associated with said friction wheel to permit the latter to be moved bodily by the load to produce friction in proportion to the latter.

20. The combination with a hoisting drum, of frictional driving apparatus geared thereto, and means associated with said driving apparatus to cause the load to increase or decrease the friction automatically.

21. The combination with a driven member, of driving apparatus therefor normally tending to go into action, means for holding it out of action, and electrical controlling means for said driving apparatus and for said holding means.

22. The combination with a hoisting drum, of a friction wheel connected thereto, a friction driving member, means for holding said friction wheel so that the degree of friction between the same and said driving member shall vary with the load, and means for disconnecting said friction wheel from said member and effecting a stopping of said hoisting drum.

23. The combination with a hoisting drum, of a friction wheel, a friction driving member for said friction wheel, means for supporting said friction wheel to effect a variation of the frictional engagement between said wheel and member dependent upon the load, a brake, and means for operating said brake to disengage said wheel and member and effect a stopping of said drum.

24. The combination with a hoisting drum, of frictional driving mechanism for said drum and dependent in its action upon variation of load, a brake for said driving mechanism, means for operating said brake to disconnect portions of the driving mechanism and effect a stopping of said drum, and stop motion apparatus for limiting the rotations of said drum to a predetermined number.

25. The combination with a hoisting drum, of a friction wheel, a friction member, speed-reducing gear between said friction wheel and said drum, means for confining said friction wheel within predetermined limits of movement, means for holding said friction wheel and friction member in engagement, a brake, and means for operating said brake to disconnect said wheel and member and to effect a stopping of said hoisting drum.

26. The combination with a hoisting drum, of a friction wheel, a friction driving member therefor, connections between said

- friction wheel and hoisting drum, a pivoted arm carrying said friction wheel, resilient means acting on said arm to effect the engagement of said friction wheel and driving member, a brake, and means for operating said brake.
27. The combination with a hoisting drum, of a friction member connected thereto, a friction driving member, resilient means for holding said members in frictional engagement with each other, a brake, means for operating said brake to disengage said members and stop the drum, and additional means for disengaging said members.
28. The combination with a hoisting drum, of a friction member, connections between said friction member and drum, a friction driving device, means for moving said friction wheel a predetermined distance and additional means for moving said friction wheel a greater distance.
29. The combination with a hoisting drum, of a wheel connected thereto, a driving member, a brake, means for operating said brake to disconnect said wheel and member, and stop the wheel, and means for disconnecting said wheel and drum.
30. The combination with a hoisting drum, of a friction wheel geared thereto, a friction driving disk, a brake for said friction wheel, means for operating said brake to disconnect said friction wheel and friction disk, and means for moving said wheel out of gear with said drum.
31. The combination with a hoisting drum, of a friction and brake wheel, gear mechanism between said wheel and drum, a friction driving drum wheel or disk co-operating with said friction and brake wheel, a brake, operating means for said brake, and means for disconnecting said gear mechanism to permit the load to operate said drum.
32. The combination with a hoisting drum, of a brake wheel, gear mechanism normally connecting said wheel and drum, a driving member for said wheel, a brake, brake-operating means, resilient means for moving the brake wheel into engagement with the driving member when the brake is released, and an emergency device for disconnecting said wheel and member and also disconnecting said wheel and drum to permit the load to operate said drum.
33. The combination with a hoisting drum, of a brake wheel, a driving disk, a brake, brake operating means, movable supporting means for said wheel, a spring for effecting an engagement of said wheel and disk when the brake is released, gear mechanism between said wheel and drum, and a pneumatic releasing device for disconnecting said gear mechanism to permit a free movement of said drum.
34. The combination with a hoisting drum, of a brake wheel, gear mechanism between said wheel and drum, a driving member, a brake, brake-operating means, a pivoted arm carrying said wheel and a pinion of said gear mechanism, yielding means for holding said wheel and member together when the brake is released, said means acting on said arm, and a pneumatic releasing device co-acting with said yielding means to move said pinion out of engagement with its gear to permit a free movement of the drum.
35. The combination with a hoisting drum, of driving mechanism, connections between said mechanism and drum, a brake, brake operating means, a releasing device for altering said connections to permit a free movement of said drum, and means for retarding such movement.
36. The combination with a hoisting drum, of driving mechanism therefor, gear mechanism between said driving mechanism and hoisting drum, a brake, brake-operating means, a pneumatic releasing device for altering said gear mechanism to allow a free movement of said drum, and a dash pot for retarding such movement.
37. In theater curtain hoisting apparatus, the combination with a curtain hoisting drum, of driving mechanism normally connected thereto, a brake, brake-operating means, a pneumatic releasing device for disconnecting said driving mechanism and hoisting drum to allow the curtain to descend by its own weight, and a dash pot for regulating the speed of such descent.
38. In theater curtain hoisting apparatus, the combination with a curtain hoisting drum, of frictional driving apparatus therefor, means for operating said driving apparatus, an emergency releasing device for automatically disconnecting said driving apparatus and drum to permit a free movement of the curtain and hoisting drum, and a dash pot for retarding such movement.
39. In theater curtain hoisting apparatus, the combination with a curtain hoisting drum, of frictional driving apparatus therefor, means for operating said driving apparatus, a pneumatic releasing device for automatically effecting a free movement of the curtain and drum, a dash pot for retarding such movement, and stop-motion apparatus for limiting the movement of said curtain.
40. The combination with a plurality of hoisting apparatuses, of driving apparatus therefor, and means for permitting gravity to act to effect connection between said hoisting apparatuses and said driving apparatus, respectively in permutations.
41. The combination with a plurality of hoisting apparatuses, of driving apparatus therefor, and releasing means to permit the action of gravity to connect any one or more of said hoisting apparatuses with said driving apparatuses at will.

42. The combination with a plurality of hoisting apparatuses, of roller frictional driving apparatus therefor, and means for controlling said driving apparatus to effect the operation of said hoisting apparatuses in permutations. 70
43. The combination with a plurality of hoisting drums, of driving mechanism for said drums, and means for controlling said mechanism to effect the actuation of a plurality of said drums together or of any one at any desired time and the stopping of each drum after making a predetermined number of revolutions. 75
44. The combination with a series of hoisting drums of a friction wheel connected to each of said drums, a driving device, and means for effecting a connection between the peripheries of said wheels and said device in any desired order. 80
45. The combination with a series of hoisting drums, of a circular rotatable member connected to each of said drums, a series of continuously driven circular rotatable members, and means for controlling the connection between the peripheries of said first-named members with the peripheries of the continuously driven members to effect the operation of said drums simultaneously or in any desired order. 85
46. The combination with a series of hoisting drums, of a plurality of friction wheels one for each of said drums, a series of friction pinions moving together, means for moving said pinions, means for controlling said moving-means, means for connecting one or more of said friction wheels to said pinions, and means for predetermining the friction wheels which shall be connected. 90
47. The combination with a series of hoisting drums, of a prime mover, means for connecting by rolling friction any one or more of said drums to said prime mover, means for controlling said prime mover, and means for predetermining the drums which shall be connected upon the operation of said controlling means. 95
48. The combination with a plurality of hoists, of brake mechanism for each hoist, electro-magnetic means for releasing said brake mechanism to effect the operation of one or more of said hoists, and means for predetermining the hoists to be operated. 100
49. The combination with a plurality of hoisting drums, of driving apparatus therefor, a plurality of brakes, one for each of said drums, electro-magnets for releasing said brakes means for controlling said driving apparatus, and means for predetermining the drums to be actuated upon the operation of said controlling-means. 115
50. The combination with a plurality of hoisting drums, of driving apparatus therefor, means for connecting by rolling friction any hoisting drum to said driving ap- 120
- paratus, electro-magnets for effecting the operation of said connecting means, and selecting apparatus for said electro-magnets to predetermine the drum or drums to be operated. 125
51. The combination with multiple hoisting apparatus, of driving means therefor, a plurality of brakes for said hoisting apparatus, electro-magnets for releasing said brakes and electro-magnetic selecting apparatus for said electro-magnets. 130
52. The combination with multiple hoisting apparatus, of driving apparatus therefor, a series of brakes, a corresponding series of electro-magnets for releasing said brakes and effecting the operation of a unit of said apparatus, controlling means for said driving apparatus, a bank of push-buttons for controlling said electro-magnets, and means for holding an operated push-button in closed position. 135
53. In multiple curtain hoisting apparatus, the combination with a series of hoisting drums, of driving apparatus therefor, brakes for said drums, electro-magnets for releasing said brakes, a bank of push-buttons for controlling said electro-magnets, electro-magnetic holding means for retaining said push-buttons in closed position until the drum corresponding thereto has been operated and stopped. 140
54. The combination with a multiple curtain hoist, of a bank of push-buttons for selecting the curtains to be moved, electro-magnetic means for holding said push-buttons in closed position, means for driving said curtain hoist, controlling means for said driving-means, and electro-magnetic brakes for said hoist and connected in circuit with said push-buttons. 145
55. The combination with multiple curtain hoisting apparatus, of a motor for operating same, means for selecting the units of said apparatus to be operated, brake mechanism, electro-magnets for operating said brake mechanism, and means for controlling and operating said motor and energizing the electro-magnets of the selected units. 150
56. The combination with multiple curtain hoisting apparatus and controlling means therefor, of a motor for operating said hoisting apparatus, an electro-magnetic selector, a manual switch, and means controlled by said switch for effecting the starting, stopping and actuation of said motor. 155
57. The combination with multiple curtain hoisting apparatus, of controlling means therefor, and electro-magnetic means for selecting the unit of the hoisting apparatus to be operated. 160
58. The combination with multiple curtain hoisting apparatus and controlling means therefor, of a motor for operating said hoisting apparatus, a bank of self- 165

holding push-buttons connected to said controlling means, and motor-controlling apparatus.

59. The combination with multiple driving apparatus, of controlling devices therefor, and an electro-magnetic selector connected to said controlling devices.

In testimony whereof, I have signed my name to this specification in the presence of two subscribing witnesses.

ANDREW M. COYLE.
